UNITED STATES PATENT OFFICE.

FRED W. MILLER, OF CHICAGO, ILLINOIS.

ICE-SCALE FOR REFRIGERATORS.

1,148,034.

Specification of Letters Patent. Patented July 27, 1915.

Application filed November 1, 1913, Serial No. 798,706. Renewed December 16, 1914. Serial No. 877,530.

To all whom it may concern:

Be it known that I, FRED W. MILLER, a citizen of the United States, residing at Chicago, in the county of Cook and State of Illinois, have invented a new and useful Ice-Scale for Refrigerators, of which the following is a specification.

The present invention appertains to ice scales for refrigerators, and aims to provide a novel and improved device of that character.

It is the object of the present invention to provide a scales particularly applicable to refrigerators, which will enable the weight of the ice within the ice chest to be readily determined.

Another object of the present invention is to provide unique means for mounting the ice tray within the refrigerator, in combination with a weighing mechanism supporting the ice tray in a peculiar manner, to carry out the results desired, in a highly efficient and desirable manner.

It is also within the scope of the invention to provide a novel assemblage of parts, in order to enhance the utility and construction of devices of the present character.

With the foregoing general objects outlined, and with other objects in view, which will be apparent as the nature of the invention is better understood, the present invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:—

Figure 1 is a plan view of a refrigerator, embodying the present appliance, the top or cover of the refrigerator case being removed, and a portion of the ice tray being broken away. Fig. 2 is a fragmental elevation of the refrigerator case illustrating the scale gradations and pointer coöperating therewith. Fig. 3 is a sectional view taken in the line 3—3 of Fig. 1.

The present invention is applicable to any suitable refrigerator case 1, an ice tray 2 being disposed loosely within the walls of the case, and forming the ice chest or compartment thereabove.

The ice tray 2 is supported by means of a U-shaped rod 3, the intermediate portion or cross bar of which is provided with seats 4 upon which the bottom of the tray 2 is secured, the arms of the member or tray-carrier 3 upstanding at the sides of the tray at right angles to the tray and having rollers or anti-frictional wheels 5 journaled upon their upper or free ends. The rollers 6 or wheels 5 are movable within vertical guides formed by pairs of upright cleats 6 secured to the inner faces of the respective walls of the case.

Disposed below the ice tray 2 is a scale lever 7, which is of V-shape, and the terminals of which are downturned to provide the pivot or fulcrum points 8, which engage a cross bar 9 carried by the case 1 at one side of the member 3. The arms of the lever 7 are pivoted to the intermediate portion of the member 3, so that the lever 7 carries the ice tray.

Secured to the crotch or free end of the lever 7 is a strap or band 10, which is secured to and adapted to be wound upon a sheave or spool 11 secured to the inner end of a shaft 12 journaled through the end wall of the case 1, and having a pointer 13 secured to its outer end.

A protractor 14, graduated to indicate pounds or other units of weight, is secured to the outer face of the respective end of the case 1 above the shaft 12, for coöperation with the pointer 13, the pointer 13 being equipped with a weight 15 adapted to normally hold the pointer at zero. The weight 15 also causes the tape 10 to be wound upon the spool 11, so as to raise the free end of the lever 7 when the ice tray is empty.

In use, the ice is placed on the tray 2, which will result in a depression of the carrier 3, thereby depressing the free end of the lever 7 against the tension of the weight 15, it being noted that when the lever 7 is depressed, the tape 10 will be unwound from the spool 11 so as to turn the shaft 12 in a direction to elevate the weight 15. The weight of the ice will thus be indicated on the gradations 14, and it will thus be possible to determine the weight of the ice placed upon the tray, or to determine at any time, the amount of ice within the refrigerator.

A cardinal or salient feature of the present invention resides in the fact that the ice

may be placed at any point upon the tray 2, without materially or appreciably affecting the weighing operation, inasmuch as the rollers 5 carried by the upstanding arms of the carrier 3, in working between the cleats 6, will prevent the ice tray from tilting, the ice tray thus being constrained to reciprocate in a true vertical direction, or parallel to itself.

10 Inasmuch as the lever 7 is fulcrumed to the cross bar 9, and the carrier 3 is pivoted to the branches of the lever 7, the ice tray will be properly carried by the lever, in order that the pointer 13 will be properly influenced by the weight of the ice within the tray.

From the foregoing, taken in connection with the drawing, the advantages and capabilities of the present device will be apparent without further comment, it being observed that the objects aimed at, have been carried out in a satisfactory manner.

Having thus described the invention, what is claimed as new is:—

- 25 1. In a device of the character described, a scale lever, a tray pivotally supported upon the lever, arms secured to the tray and arranged at right angles thereto, guides adjacent the said arms, rollers carried by the 30 free ends of the said arms and engaging the guides, and weight-indicating means operatively connected to the lever.
2. In a device of the character described,

a scale lever, a U-shaped member having its intermediate portion pivoted upon the lever, a tray secured upon the intermediate portion of the U-shaped member, guides, the free ends of the arms of the U-shaped member engaging the guides, and weight-indicating means operatively connected to the lever.

3. In a device of the character described, a V-shaped lever having terminal fulcrums, a U-shaped member having its intermediate portion pivoted to the branches of the lever, a tray secured upon the intermediate portion of the U-shaped member, means for guiding the free ends of the arms of the U-shaped member, and weight-indicating means operatively connected to the crotch of the lever.

4. In combination with a case, a scale lever fulcrumed therein, a U-shaped member having its intermediate portion pivoted to the lever, a tray secured upon the intermediate portion of the U-shaped member, guides carried by the case, rollers carried by the arms of the U-shaped member and engaging the guides, and weight-indicating means operatively connected with the lever.

In testimony that I claim the foregoing as my own, I have hereto affixed my signature in the presence of two witnesses.

FRED W. MILLER.
